UNITED STATES PATENT OFFICE.

JOHN T. LYNCH, OF CHICAGO, ILLINOIS, ASSIGNOR TO THE B. F. CUMMINS COMPANY,
A CORPORATION OF ILLINOIS.

SEPARATING MECHANISM FOR MAIL-MATTER.

1,058,314.

Specification of Letters Patent.

Patented Apr. 8, 1913.

Application filed February 20, 1911. Serial No. 609,724.

To all whom it may concern:

Be it known that I, JOHN T. LYNCH, a citizen of the United States, residing at Chicago, in the county of Cook and State of Illinois, have invented certain new and useful Improvements in Separating Mechanism for Mail-Matter, of which the following is a description, reference being had to the accompanying drawings, forming a part of this specification, in which corresponding letters of reference in the different figures indicate like parts.

The object of my invention is to provide a simple and effective separating mechanism for mail matter applicable to post-marking and other similar machines for handling mail, which shall be so constructed as to cause a satisfactory separation of the mail-pieces as they are advanced upon a conveyer while preventing them from becoming clogged when a number are presented at once or in too rapid succession.

To these ends my invention consists in the combination of elements hereinafter more particularly described and definitely set forth in the claims.

In the example illustrated, I have shown the device applied to an ordinary post-marking machine in which it is necessary to separate the mail-pieces before they are presented to the canceling die.

Figure 1, is a plan view of a portion of a post-marking machine showing the usual conveyer belt, feed mechanism and marking die with my improved separator as it would appear when applied thereto, Fig. 2, is a like view showing the conveyer and feed mechanism as they would appear with a considerable number of mail-pieces presented for separation, and Fig. 3, is an enlarged detail view showing the construction of the joint between the two presser plates.

Referring to the drawings, 1 represents the table of an ordinary post-marking machine upon which is mounted the usual conveyer belt 2, supported at its ends upon horizontal rollers in a well known way. A feed-belt 3, mounted upon pulleys 4, having vertical axes, one only of which is shown, is adapted to convey the mail-pieces in the usual way to a marking die 5. A shield 6, for supporting and directing the mail-pieces in the proper path together with the usual

impression roller 7 and timing finger 8, with other mechanism essential to their operation, 55 but not herein claimed, are shown but need not be described at length.

A vertical shield plate 9, is rigidly supported in any approved way above and lengthwise of the conveyer belt 2, to form a 60 side wall or support for such mail-pieces 10, as may be advanced upon the conveyer belt which may be of indefinite length, so that letters may be placed thereon singly or in bunches as they are delivered to any ordinary canceling machine or it may be utilized in conjunction with the runway or chute of a pick-up-table. Hinged at 11 to the part 9, is a yielding wing-section or presser-plate 12, the forward portion of which upon its inner 70 face, is serrated as shown at 13. An arm 14, is rigidly attached to the back of the plate 12 the free end of which is adapted to rest normally against an adjustable stop consisting of a set-screw 15, tapped into a bracket 16, rigidly attached to the frame. A spring 17, is attached to said bracket and arranged to press against the back of the plate 12, so as to normally hold the latter in the position shown in Fig. 1 with the end of the plate 80 very close to the surface of the feed-belt 3, the space between the two being only sufficient to permit the forward end of a mail-piece to enter. The adjustment may be effected by means of the set-screw 15. Jointly connected to the forward end of the wing-section 12, as shown at 18, is a shorter member or section 19, which is also serrated upon its inner face as shown. A short rod 19a is jointedly connected at 20 to a lug upon 90 the back of the forward end of the wing-section 19, which rod is arranged substantially at right angles to the letter-path and is loosely projected through a bore in a stud 21, which is attached to the frame. A coiled 95 spring 22, upon the rod serves to normally hold the forward end of the wing in close proximity to the belt 3, the exact position being determined by means of adjustable lock nuts 23.

The joint 18 is preferably elongated as shown at 24, so as to permit of a lateral play between the two wings for the purpose of temporarily arresting the advance of such mail pieces as may be moving in a compact 105 bunch in the outer portion of the path or

next to the wing 12 and prevent them from wedging into the throat of the device before those nearer to the feed belt can be advanced.

I have indicated in the drawings what I have regarded as the best disposition of the sections 12 and 19, with respect to the beginning of the feed mechanism; that is to say, that a portion at least of one of said sections, preferably the section 12, should be arranged to precede the beginning of the operation of the feed mechanism as shown, while a portion at least of the other is located in advance thereof.

Inasmuch as the wing-sections 12 and 19 are made of metal, the fractional surfaces may not always be sufficient to insure complete separation. As a means of precaution therefore, I preferably employ a reverse separating roller 25 at the forward end of the wing 19 and close to the feed-belt, in conjunction with the separating device described.

I prefer to make the spring which presses against the wing-section 12 somewhat stronger than that which controls the section 22 for the reason that it is frequently required to resist greater lateral pressure. This is especially true when the separator is used in conjunction with a pick-up-table where it is customary for the operators to place an entire bunch of "faced" mail-pieces upon the conveyer belt without any attempt at separation. When such a bunch is brought into contact with the section 12 it is moved laterally to such an extent as would permit the passage of two or more of those nearest the feed belt. This result, however, is prevented by the action of the section 19 which is independently pressed by the spring 22 and serves to retard all but one of the advanced mail-pieces. Another difficulty is liable to occur, however, in presenting a compact bunch to the separator and that is, if too many are permitted to enter the throat at once they may become wedged so as to delay or prevent the proper action. The play in the joint between the two sections tends to overcome this difficulty by permitting the knuckles upon the section 19 to stand slightly nearer to the feed belt than those upon the section 12 and thus form a temporary obstruction to prevent the advancement of the bunch too far into the throat of the separator. This continues until the mail-pieces adjacent to the belt are advanced thereby and the excessive width of the pack reduced. The lateral play in the joint needs to be but slight and under ordinary working conditions is not necessary at all.

Having thus described my invention, what I claim and desire to secure by Letters-Patent is:—

1. In a device of the class described, the combination with feed mechanism for con-

veying mail-pieces endwise in a given path, of separating means consisting of a presser-wing comprising a plurality of sections jointedly connected to each other, said sections being arranged adjacent to said path, yielding means for exerting a pressure upon each section to press it toward the mail-pieces, said sections being arranged to assume varying angles with respect to the mail-piece path in conformity to the varying counter-pressure of the mail-pieces, the rear end of the rear section being jointedly connected to the wall adjacent to the mail-piece path.

2. In a device of the class described, the combination with conveying and feeding means of a separator comprising a presser-wing composed of sections jointedly connected to each other, the rear end of the rear section being hinged to a stationary point adjacent to the path of the mail-pieces and separate means for exerting a yielding pressure upon the back of each section to press said sections toward the feeding mechanism at an angle to the path of the mail-pieces and means for limiting the movement of said sections.

3. The combination with a conveyer belt disposed in a horizontal plane, of feeding mechanism disposed in a vertical plane for advancing mail-pieces endwise, a presser-wing located above said conveyer belt the same being arranged to form a converging path toward said feeding mechanism, said presser-wing being composed of a plurality of sections jointedly connected to each other, the rear end of the rear section being hinged to a stationary point and means for exerting a yielding pressure upon the back of each section.

4. In a device of the class described, the combination of a conveyer belt and feed-mechanism, of a sectionally jointed presser-wing located at the juncture of said belt and feeding mechanism, and arranged to extend toward the latter to form a converging pathway for mail-pieces, the rear end of said wing being hinged to a stationary point, means for exerting a yielding pressure upon the back of each wing-section and means for permitting a play in the joint between said sections.

5. In a device of the class described, the combination of a conveyer belt and feed-mechanism, of a sectionally jointed presser-wing arranged convergently toward said feed-mechanism to deflect the mail-pieces thereto as they are advanced upon the conveyer-belt, adjustable means for limiting the lateral movement of the sections of said wing and separate springs for pressing the free ends of said sections toward said feed-mechanism.

6. In a device of the class described, the combination of a conveyer-belt and feed-

mechanism, of a presser-wing composed of a plurality of connected sections, said wing being arranged convergently toward said feed mechanism with its forward end adjacent to the latter to deflect mail-pieces thereto as they are advanced upon the conveyer belt, springs for independently pressing against the backs of said respective sections and a jointed connection between said sections to permit a lateral play between the connected ends of the two, whereby one may be advanced farther into the path of the mail-pieces than the other when a lateral outward pressure is exerted by the mail-pieces upon its fellow.

7. The combination with a conveyer-belt disposed in a horizontal plane of feeding means disposed in a vertical plane for advancing mail-pieces endwise upon their edges, a presser wing located above said conveyer belt, the same being arranged to form a converging path toward said feeding means, said presser-wing being composed of a plurality of sections jointedly connected to each other, the rear end of the rear section being hinged to a stationary point and separate springs for exerting a pressure upon the back of each section, the spring controlling

the first section being stronger than that which controls the second.

8. In a device of the class described, the combination with feed mechanism for conveying mail-pieces endwise in a given path, of separating means consisting of a presser wing disposed obliquely to the mail-piece path and in operative proximity thereto, said wing comprising a plurality of sections jointedly connected to each other and means for separately exerting a yielding pressure upon each section to press said section toward the mail-pieces, to enable the former to normally assume varying angles with respect to the mail-piece path, a portion, at least, of one of said sections being arranged to precede the beginning of the operation of the feed mechanism while a portion, at least, of another is located in advance thereof.

In testimony whereof, I have signed this specification in the presence of two subscribing witnesses, this 18th day of February, 1911.

JOHN T. LYNCH.
